UNITED STATES PATENT OFFICE.

HEINRICH RILL, OF SOLINGEN, GERMANY, ASSIGNOR OF ONE-HALF TO VINCENZ RILL,
OF SOLINGEN, GERMANY.

APPARATUS FOR PRESSING DENTS IN BAKERY ROLLS.

Application filed October 1, 1926. Serial No. 138,967.

This invention relates to an improved apparatus for simultaneously pressing the dents in a plurality of bakery rolls, which is illustrated on the accompanying drawing, 5 in which:

Fig. 1 is a perspective view of the same, with part of the outer casing broken away to show the inner mechanism of the apparatus,

10 Fig. 2 is an end view of part of said mechanism,

Fig. 3 is a longitudinal section through part of the apparatus, and

15 Fig. 4 is a cross-section through a detail of the same on a larger scale.

The apparatus comprises an outer casing *a* of wood or metal. Within said casing, a pressure-plate *b* is arranged. On the upper side of the latter, two vertical toothed racks *c* are fixed at a distance from one another and led through guiding-slots in the top of said casing and through openings in a guiding-ledge *i* fixed in the latter, while on a horizontal revoluble shaft *d* in said casing two pinions *h* are keyed and in gear with said toothed racks. Said shaft *d* projects at one end beyond the casing *a* and carries there a wheel *g* with a crank-handle *f*, by which the shaft can be rotated and thus the pressure-plate *b* can be moved up and down.

20 On each of two opposite ends of said pressure-plate *b* a plurality of, for instance six, depending brackets *k* are fixed by means of nuts *k*¹ screwed above and below said pressure-plate on a screw-threaded part of said brackets, so that the position of height of the latter can be easily adjusted by means of said nuts. Each two opposite brackets *k* carry at their lower ends a revoluble pressure-bar *l*.

25 As shown in Figs. 3 and 4, between the pressure-plate *b* and each pressure-bar *l* an oil bolster *n* is suspended loosely from the brackets *k* so as to bear at its underside directly upon the pressure-bar *l*, an oil container *o* (Fig. 4) being located on the pressure-plate *b* and provided with very narrow depending supply pipes *o*¹ which feed the

oil in drops to the upper grooved oil-permeable surface *n*¹ of said bolsters, whereby the pressure-bars *l* are slightly lubricated in a continuous way. For sake of clearness, the oil container *o* with its supply pipes *o*¹ has been omitted from Figs. 1 and 3. The lower surface of the oil bolsters is concave, while below the adjacent sides of each two oil bolsters a gutter *p* is provided for the reception of the excess oil dropping from said bolsters, said gutters preventing at the same time a sticking of the roll *x* to the pressure-bar *l* during the ascent of the latter after having pressed the dent in the roll. For this purpose, the rolls *x*, which are placed in grooves *r* of a board *q* upon which said gutters are fixed, are of corresponding length so that they abut with their ends against the underside of said gutters in case that they are unintentionally lifted with the pressure-bars by sticking thereto. The board *q* can be laterally inserted in and removed from the casing *a* through a slot therein (not shown) and placed upon the bottom *s* of the latter.

30 The rotation of the pressure-bars *l*, during the up and down movement of the same together with the pressure-plate *b*, is effected by means of pinions *t* keyed on the outwardly projecting ends of said bars, the outermost of said pinions being in gear with a toothed-rack fixed to the outside of the casing *a*, while the projecting ends of said pressure-bars are guided in vertical slots *v* in said casing.

35 The operation is as follows: By turning the crank handle *f* in one direction, the pressure-plate *b* together with the well lubricated pressure-bars *l* are lowered with a simultaneous rotation of the latter until the desired dents are pressed in the rolls *x*, while by a rotation of the crank handle *f* 40 in the opposite direction, the pressure-plate with the pressure-bars are again lifted.

45 What I claim, is:

1. The combination, in an apparatus for simultaneously pressing dents in a plurality of bakery rolls, of up and down movable

and simultaneously rotating pressure-bars, and loosely suspended oil bolsters in direct contact with said pressure-bars during the up and down movement of the latter.

- 5 2. In an arrangement as specified in claim 1, means for separately feeding each oil bolster with oil.
3. In an arrangement as specified in claim

1, means for collecting the excess oil dropping from said oil bolsters and at the same time preventing the rolls from sticking to the returning pressure-bars after their treatment.

In testimony whereof I have hereunto set my hand.

HEINRICH RILL.
